UNITED STATES PATENT OFFICE

2,640,474

SPARK PLUG

Harold P. Phillips, Hastings, Mich., assignor to
Hastings Manufacturing Company, Hastings,
Mich.

Application October 1, 1951, Serial No. 249,134

2 Claims. (Cl. 123—169)

1

This invention relates to improvements in spark plugs.

The main objects of this invention are:

First, to provide a spark plug in which the electrodes are all within and guarded by the insulator shell of the spark plug and at the same time one in which the ground electrode may be very easily and quickly adjusted relative to the insulated electrode.

Second, to provide a spark plug insulator shell and ground electrode assembly having these advantages which may be very economically produced.

Objects relating to details and economies of the invention will appear from the description to follow. The invention is defined and pointed out in the claims.

A preferred embodiment of the invention is illustrated in the accompanying drawing, in which:

Fig. 1 is a perspective view of a spark plug embodying my invention.

Fig. 2 is an enlarged inner end view with an adjusting tool shown in section positioned for the spark gap adjusting a ground electrode.

Fig. 3 is an enlarged fragmentary view partially in section on a line corresponding to 3—3 of Fig. 2.

Fig. 4 is an end elevational view of the shell slotted to receive the ground electrodes and the tool abutment elements.

Fig. 5 is an enlarged fragmentary view on a line corresponding to 5—5 of Fig. 2.

Fig. 6 is a fragmentary view partially in section corresponding to that of Fig. 3 of a modified form or embodiment of my invention.

In the accompanying drawings the view are considerably enlarged as compared to commercial structures; this being done for clearness and convenience in illustration.

In the embodiment illustrated in the accompanying drawings the spark plug comprises the insulator 1 and the insulator shell 2 having an external threaded portion 3 adapted to be threaded into a suitable bore provided therefor in a cylinder head or block. The insulated electrode 4 is mounted and sealed within the insulator 1 to project from the inner end thereof. The details of mounting the insulator within the shell and the insulated electrode within the insulator are not illustrated as they form no part of my present invention.

The shell 2 is provided with slots 5 disposed in angularly spaced nonaligned relation and opening to and extending from its inner end. Bend-

2

able ground electrodes 6 are disposed in and welded in the slots as is best shown at 7 in Figs. 3 and 5. These electrodes in the embodiment illustrated are disposed in parallel relation with their inner ends overlapping each other and in spaced lapping relation to the insulator electrode 4. The electrodes are all within and guarded by the shell.

It is recognized that the spacing or spark gapping of the ground electrode relative to the insulated electrode is an important factor in the efficient operation of an internal combustion engine.

To facilitate the adjustment of the ground electrodes I provide tool supporting abutment elements 8 which are disposed in generally opposed relation to the free ends of the ground electrodes but spaced therefrom and preferably in inclined offset relation thereto so that a tool such as a screw driver blade 9 may be positioned in supporting fulcruming engagement with an abutment element for engagement with the end of an electrode and facilitating the accurate adjustment thereof.

25 The shell is provided with slots 10 open to the inner edge thereof and dimensioned to receive the elements 8 which are welded therein as indicated at 11. The slots 10 and the securing of the elements 8 therein is the same as the slots 5 receiving the ground electrodes. The slots 10 are desirably radially positioned relative to the axial center of the shell as is shown in Figs. 2 and 4 which results in the easy positioning of the abutment elements.

35 In the modification shown in Fig. 6 the abutment element 11 corresponding to abutment elements 8 are inserted in and fixedly secured in bores 12 instead of in slots but the tool supporting elements 11 are disposed in generally the same relation of the inner ends of the electrodes of Fig. 2 as shown in the preferred embodiment, so that they serve as supports for tools for adjusting or gapping the ground electrodes. The embodiment shown in Figs. 1 to 5 inclusive is however preferred in that it has substantial manufacturing economies as compared to embodiments shown in Fig. 6.

With this arrangement of parts the ground electrodes may be quickly and easily and accurately gapped at the factory when the spark plug is designed and packaged for the requirements of the particular engine and also to compensate for manufacturing errors. They may be quickly gapped by the installer when used for replacement purposes. This is a very great convenience

as a spark plug may be quickly adjusted to meet the requirements of the particular engine.

I have illustrated and described two practical embodiments of my invention. I have not attempted to illustrate or describe certain other modifications or adaptations which I contemplate as it is believed those skilled in the art will be able to embody or adapt my invention as may be desired.

Having thus described my invention, what I claim as new and desire to secure by Letters Patent, is:

1. A spark plug insulator shell and ground electrode assembly comprising an insulator shell having angularly spaced nonaligned slots opening to and extending from its inner end, bendable ground electrodes disposed in parallel relation within said shell and guarded thereby and with their outer ends within and welded in said slots and with their inner ends free and disposed in oppositely directed laterally spaced overlapping relation to each other and to the axial center of the shell, said shell having other slots opening to and extending from its inner end and disposed in angularly spaced relation to said ground electrode receiving slots, and tool abutment elements disposed and welded in said other slots with their inner ends projecting into the shell in opposed angularly inclined laterally spaced relation to the free ends of the ground

electrodes facilitating the adjustment of an electrode relative to the axial center of the shell by a tool in supported engagement with the opposed abutment element.

2. A spark plug insulator shell and ground electrode assembly comprising an insulator shell having a slot opening to and extending from its inner end, a bendable ground electrode disposed within said shell and guarded thereby and with its outer end within and welded in said slot and with its inner end free, said shell having another slot opening to and extending from its inner end, and a tool abutment element disposed and welded in said other slot with its inner end projecting into the shell in generally opposed angularly inclined laterally spaced relation to the free end of the ground electrode facilitating the adjustment of the electrode relative to the axial center of the shell with a tool in supported engagement with the abutment element.

HAROLD P. PHILLIPS.
